OF NEW YORK, N. Y., A CORPORATION OF NEW JERSEY.

CAP FOR FRICTION-TOP CANS.

1,200,354.

Specification of Letters Patent.

Patented Oct. 3, 1916.

Application filed December 13, 1913. Serial No. 206,355.

To all whom it may concern:

Be it known that I, JOHN G. HODGSON, a citizen of the United States, residing in Maywood, in the county of Cook and State of Illinois, have invented a new and useful Improvement in Caps for Friction-Top Cans, of which the following is a specification.

This invention relates to improvements in caps for friction top cans.

The object of the invention is to provide a cap for combined hermetically and frictionally sealed food containing cans, the cap having a peripheral gasket or hem composed of a compressible and elastic material.

Friction top cans have been known in the art for many years and the same have generally been used for inclosing substances which are not seriously affected by small admissions of air to the interior of the cans, the friction seal being one which is not an absolutely hermetic seal. The substances most commonly packed in friction top cans are ordinary paints, varnishes, powdered or comminuted substances and a few kinds of food products. Hitherto, in inclosing most food products and the higher grades of paints and varnishes which are more or less affected by continued exposure to air, it has been the practice to inclose such substances either in soldered top cans or what are commonly termed sanitary or double seamed cans. There has been a long felt need for a can having the advantages of the friction top can and in which could be inclosed substances that must be perfectly and absolutely protected from contact with the atmosphere; or, in other words, a perfectly hermetically sealed can having a friction cover or top. I have devised such a can and the same includes in addition to the usual friction top, a cap having a compressible and elastic gasket which is held firmly seated on a coöperating supporting ledge of the can top by means of the friction cover.

In the drawing such a can as I have described is illustrated, Figure 1 thereof being a vertical sectional view and Fig. 2 being an enlarged sectional view of the improved cap employed in connection therewith.

In said drawing, the can body is designated by the reference 10, the same having

a bottom 11 soldered or otherwise secured thereto and provided also with a top 12. The top 12 is provided with two spaced, substantially vertically extending friction seat walls 13 and 14, an annular, upwardly extended bead 15 at the top of the friction wall 14 and an upwardly inclined ledge or supporting shelf 16 surrounding the usual central opening therein. Coöperable with the can top is a friction cover 17 having a pryoff rim 18, spaced, substantially vertically extending friction seat walls 19 and 20 and central portion 21, the friction seat walls of the cover coöperating with those of the can top in the usual manner. The improved cap, as shown, comprises a circular sheet metal member 22 having a countersunk central portion 23, and downwardly inclined peripheral edge 24, the latter having secured thereto an annular, compressible and elastic gasket 25 of substantially U-shape in cross-section, which gasket or hem may be made of rubber, rubber compound, fibrous material or other suitable substance adapted to be easily compressed and to accommodate itself to any irregularities or crevices in the member against which it is pressed. As shown in Fig. 1 of the drawing, the cap 22 is placed over the opening in the can top with the gasket or hem thereof resting on the upwardly inclined shelf 16. The friction cover, when forced home, will engage the top portion of the cap and press it firmly into engagement with the can top, thereby providing an hermetic seal for the can in addition to the two friction seals formed between the two sets of coöperating friction seat walls.

From the preceding description it will be seen that the can is adapted to contain all kinds of substances which must be protected from the atmosphere and at the same time the can has all the characteristics and advantages of the ordinary friction top can. The can which I have provided is suitable for containing the highest grades of paints and varnishes and the seal formed is such as to absolutely prevent any skin forming on the top thereof which has hitherto been found to occur when such materials have been shipped in the ordinary friction top cans. My improved can is also adapted for use in preserving food products of all descriptions, both in factory canning and household canning, the construction being

such that the cap and cover may be applied without the use of any complicated machinery.

I am aware that caps for soldered cans have hitherto been made which have been provided with a hem of common solder or other fusible metal, but such caps are not within the purview of my invention inasmuch as they do not have a gasket which is compressible or elastic nor one in which the seal is adapted to be affected merely by means of pressure between two parts. The solder hem caps to which I refer, are merely designed for applying the solder in a convenient manner to the point where needed, the solder being melted and fused after the can cap has been applied to the stud hole of the soldered can, which does away with the necessity of applying the solder after the caps have been put in place.

What I do claim, however, is:

1. A frictionally and hermetically sealed can, comprising in combination: a can the top of which is formed with an inwardly presented gasket-engaging shoulder and with an outwardly presented friction wall at the outer side of the said shoulder; a cap comprising a sheet metal body having an outwardly presented gasket-engaging part; said cap being adapted to seat loosely on the can top; a gasket between the said inwardly presented shoulder and said outwardly presented cap part; and a cover having an inwardly presented friction wall adapted to press firmly against the said outwardly presented friction wall of the can top to force said shoulder toward the gasket when said cover is applied.

2. A frictionally and hermetically sealed can, comprising in combination: a can the top of which is formed with an outwardly and downwardly inclined cap-supporting ledge; a cap comprising a sheet metal body formed with a downwardly and outwardly inclined sheet metal rim and formed at the upper end of said downwardly and outwardly inclined sheet metal rim with a stiffened cover-engaging bead; said cap being provided with a gasket attached to said downwardly and outwardly inclined sheet metal rim and adapted to rest loosely on said outwardly and downwardly inclined cap-supporting ledge; and a cover having an inwardly presented cap-engaging surface adapted to engage said stiffened cover-engaging bead of the said cap to press the gasket firmly against the cap-supporting ledge when the cover is applied; and friction walls securing said cover to the can top.

3. A frictionally and hermetically sealed can, comprising in combination: a can the top of which is formed with an inclined flange-portion around an open mouth, and with a friction wall at the outer side of the said inclined flange portion; a cap comprising

ing a sheet metal body formed with a downwardly and outwardly inclined sheet metal rim flange and having a gasket at the edge of the same; said downwardly and outwardly inclined sheet metal rim flange of the cap being adapted to seat loosely on said flange-portion of said can top with said gasket interposed; and a cover having an inwardly presented friction wall adapted to press firmly against the said outwardly presented friction wall of the can top to force gasket-supporting parts of the can top toward the gasket and cap when said cover is applied.

4. A frictionally and hermetically sealed can, comprising in combination: a can the top of which is formed with an inwardly and downwardly inclined flange-portion and with an outwardly presented friction wall at the outer side of the said inclined flange-portion; a cap comprising a sheet metal body formed with a downwardly and outwardly inclined sheet metal rim flange and having a gasket at the outwardly presented edge of the same; said downwardly and outwardly inclined sheet metal rim flange of the cap being adapted to seat loosely on said flange-portion of said can top; and a cover having an inwardly presented friction wall adapted to press firmly against the said outwardly presented friction wall of the can top to force gasket-supporting parts of the can top toward the gasket and cap-edge when said cover is applied.

5. In a frictionally and hermetically sealed can, in combination: a cap adapted to effect a hermetic seal, and comprising a sheet metal body formed with a downwardly and outwardly inclined sheet metal rim flange; a gasket of compressible and elastic material attached to the under side of said rim flange; a can the top of which is formed with an outwardly and downwardly inclined wall on which the said gasket fits, and with an outwardly presented friction wall at the outer side of the said inclined wall; and a cover formed to press down on the said cap and gasket, and having an inwardly presented friction wall which presses the outwardly presented friction wall of the can top and the gasket supporting parts toward the gasket.

6. In a frictionally and hermetically sealed can, in combination: a cap adapted to effect a hermetic seal, and comprising a sheet metal body formed with a downwardly and outwardly inclined sheet metal rim flange; a gasket of compressible and elastic material attached to the under side and to the edge of the said rim flange; a can the top of which is formed with an outwardly and downwardly inclined wall on which the under side of the said gasket fits, and with an upwardly and outwardly inclined wall against the base of which the edge portion

of the gasket fits, and with an outwardly presented friction wall at the outer side of the said upwardly and outwardly inclined wall; and a cover formed to press down on the said cap and gasket, and having an inwardly presented friction wall which presses the outwardly presented friction wall of the can top, and the said upwardly and out-

wardly inclined wall of the same, toward the edge of the gasket. ¹⁰

Signed this 9th day of December, 1913,
in the presence of two witnesses.
